[57] CLAIM

The ornamental design for an armchair, substantially as shown and described.

DESCRIPTION

FIG. 1 is a perspective view of an armchair made in accordance with the design of my invention; FIG. 2 is a front elevational view of the armchair; FIG. 3 is a side elevational view of the armchair; FIG. 4 is a rear elevational view of the armchair; FIG. 5 is a top plan view of the armchair; FIG. 6 is a bottom plan view of the armchair; FIG. 7 is a rear perspective view of the armchair; FIG. 8 is a perspective view of an alternative embodiment of my design in which a four-legged base is employed instead of a five-legged base; FIG. 9 is a front elevational view of an alternative embodiment of my design in which button tufting is used in the cushioning; FIG. 10 is a top plan view of the alternative embodiment of FIG. 9; FIG. 11 is a perspective view of another alternative embodiment of my design in which a differently styled base is employed; FIG. 12 is a generally rear perspective view of yet another alternative embodiment of my design wherein there is a demarcation between the upper portion of the chair back and the lower portion thereof; FIG. 13 is a side elevational view of the alternative embodiment armchair shown in FIG. 12; FIG. 14 is a rear elevational view of the alternative embodiment armchair shown in FIG. 12; and FIG. 15 is a bottom plan view of the alternative embodiment armchair shown in FIG. 12.
